US00D570143S

(12) **United States Design Patent** (10) **Patent No.:** **US D570,143 S**
Bigelow (45) **Date of Patent:** **** Jun. 3, 2008**

(54) **BATHROOM TISSUE ROLL STORAGE APPARATUS**

D541,564 S * 5/2007 Snell D6/520
D550,488 S * 9/2007 Nip et al. D6/521

(76) Inventor: **Brad Bigelow**, 1638 Imperial Palm Dr.,
Apopka, FL (US) 32712

* cited by examiner

(**) Term: **14 Years**

Primary Examiner—Brian N Vinson

(21) Appl. No.: **29/289,071**

(74) *Attorney, Agent, or Firm*—Larry D. Johnson

(22) Filed: **Jul. 5, 2007**

(57) **CLAIM**

(51) **LOC (8) Cl.** **20-02**

The ornamental design for a bathroom tissue roll storage apparatus, as shown and described.

(52) **U.S. Cl.** **D6/520; D6/521**

DESCRIPTION

(58) **Field of Classification Search** D6/518-523;
206/389, 391; 211/13.1, 59.1, 45, 890.1;
242/570, 590; 248/309.1, 309.2

FIG. 1 is an upper right front perspective view;

See application file for complete search history.

FIG. 2 is a front elevation view;

(56) **References Cited**

FIG. 3 is a left side elevation view, the right side is a mirror image thereof;

U.S. PATENT DOCUMENTS

FIG. 4 is a rear elevation view; and,

D518,985 S * 4/2006 Yang et al. D6/521
D528,836 S * 9/2006 Petersen-Rutten D6/521

FIG. 5 is a top plan view; the bottom view is unornamented and contains no design feature.
